TOY ROLY-POLY OR THE LIKE

Carla Greene, Chicago, Ill.

Application June 15, 1949, Serial No. 3,288

Term of patent 14 years

(Cl. D34—15)

To all whom it may concern:

Be it known that I, Carla Greene, a citizen of the United States, residing at Chicago, in the county of Cook and State of Illinois, have invented a new, original, and ornamental Design for a Toy Roly-Poly or the like, of which the following is a specification, reference being had to the accompanying drawing, forming part thereof.

In the drawing Figure 1 is a front view, and Figure 2 is a side view of a toy roly-poly or the like, showing my new design.

I claim:

The ornamental design for a toy roly-poly or the like, substantially as shown.

CARLA GREENE.
